JOHANN F. M. PATITZ, OF MILWAUKEE, WISCONSIN, ASSIGNEE, BY MESNE ASSIGNMENTS, TO ALLIS-CHALMERS MANUFACTURING COMPANY, A CORPORATION OF DELAWARE.

GAS DESICCATION.

1,113,682.

Specification of Letters Patent. Patented Oct. 12, 1914.

Application filed December 21, 1908. Serial No. 468,441.

To all whom it may concern:

Be it known that I, JOHANN F. M. PATITZ, a citizen of the United States, residing at Milwaukee, in the county of Milwaukee and State of Wisconsin, have invented a certain new and useful Improvement in Gas Desiccation, of which the following is a specification.

This invention relates to an improved method of gas desiccation and is particularly adapted for desiccating or drying air which is to be forced through a mass of combustible substances such as is found in blast furnaces where the pressure of the air blast is approximately fifteen pounds gage.

The object of the invention is to remove moisture from the air without necessitating a high compression thereof thus reducing the tendency of having leaky joints or bursting pipes in the apparatus.

A clear conception of the invention can be obtained by referring to the accompanying drawing which represents the invention applied to an air drying system.

The prime mover 6 of the compressors 1, 5, may be a turbine or any suitable engine, either steam, gas, hydraulic or electric. The prime mover 6 is direct connected by means of the linkage 61 to a compressor 1. The linkage 61 is either a shaft, as when turbines are used, or a piston rod and connecting rod or rods when reciprocating machinery is used. This compressor 1, having its suction through pipe 10, compresses atmospheric air up to say ten to fifteen pounds gage pressure, discharging the compressed air through the pipe 12 which leads to the surface cooler 2. In this cooler 2 the heat due to compression in the compressor 1 is carried off by means of any suitable medium, such as water. The cooling water enters the cooler 2 through the pipe 21 and passes through the cooling tubes or pipes 20 and is discharged through the pipe 22.

During its passage through the tubes 20, the cooling medium absorbs the heat of compression from the compressed air which surrounds the tubes 20, thus leaving the discharged compressed air at approximately the same temperature as that of the inlet cooling medium. The compressed air from the cooler passes through the pipe 23 into the expanding engine 3 which is direct connected to the linkage 61 so that during the operation of expanding the compressed

air to atmospheric pressure the expanding engine 3 will assist the prime mover 6 in performing the work of driving the compressor 1 hereinabove mentioned and the compressor 5 hereinafter mentioned. As the air expands to atmospheric pressure in the engine 3, it deposits most of its moisture in the form of water, frost or snow in the snow pockets 4, having the door 8 for removal of snow. This deposition of the moisture is facilitated by the abstraction of heat in the cooler before expansion in the engine 3. The expansion of air in the engine 3 and the translation of heat thereof into work necessarily causes a decrease in temperature which will be sufficient to liquefy or freeze the contained moisture. After the deposit of the moisture in the form of water or snow in the snow pocket 4, the air at atmospheric pressure passes through the pipe 45 into a second compressor 5, also direct connected to linkage 61, in which it is compressed to the pressure required for use.

In blast furnace application, the air after leaving the compressor 5 through the pipe 15, is heated up to the required temperature. When applied to blast furnace use, the essential point is not so much the removal of moisture as the removal of moisture to leave the air with as nearly as possible constant percentage of moisture. If it were economically possible, entire removal of moisture would be the most desirable condition.

Other uses may be found for air constant in amount of moisture.

It should be understood that it is not desired to be limited to the exact details of construction shown and described, for obvious modifications will occur to a person skilled in the art.

It is claimed and desired to secure by Letters Patent,—

1. The process of desiccating gas by compressing the gas, cooling the compressed gas, expanding the cooled gas to about atmospheric pressure, removing the condensed moisture and compressing the desiccated gas as desired for use.

2. The process of desiccating gas for use above atmospheric pressure, by compressing the gas, cooling the compressed gas, expanding the cooled gas to a pressure at or above atmospheric pressure, removing the con-

dened moisture and compressing the desiccated gas as desired for use.

3. The process of desiccating gas by compressing the gas, cooling the compressed gas, expanding the cooled gas to about atmospheric pressure, utilizing the work of compression during one of the two preceding steps of the process, removing the condensed moisture, and compressing the desiccated gas as desired for use.

4. The process of desiccating gas for use above atmospheric pressure by compressing the gas, cooling the compressed gas, ex-

panding the cooled gas to a pressure at or above atmospheric pressure, utilizing the work of compression during one of the two preceding steps of the process, removing the condensed moisture, and compressing the desiccated gas as desired for use.

In testimony whereof, I affix my signature 20 in the presence of two witnesses.

JOHANN F. M. PATITZ.
